UNITED STATES PATENT OFFICE.

OSCAR NELSON, OF CHICAGO, ILLINOIS.

SPOOL FOR PERFORATED MUSIC-SHEETS.

1,080,229.

Specification of Letters Patent.

Patented Dec. 2, 1913.

Application filed February 21, 1910, Serial No. 545,188. Renewed October 4, 1911. Serial No. 652,849.

To all whom it may concern:

Be it known that I, OSCAR NELSON, a citizen of the United States, residing at Chicago, in the county of Cook and State of Illinois, have invented certain new and useful Improvements in Spools for Perforated Music-Sheets, of which the following is a specification.

This invention relates to improvements in that class of spools or rollers on which perforated sheets of music are wound, and which spools are used in connection with self-playing musical instruments, and it consists in certain peculiarities of the construction, novel arrangement, and operation of the various parts thereof, as will be herein-after more fully set forth and specifically claimed.

The main object of the invention is to provide a spool of the above-named character, which shall be simple and inexpensive in construction, strong, durable, and so made that the body of the spool on which the sheets are wound can be readily secured in place on the supporting frame therefor, or easily and quickly removed therefrom, and will serve as a protection for the sheets in handling or shipping the same.

Other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1, is a view partly in elevation and partly in section of a spool embodying the invention; Fig. 2, is an inner face view of one of the flanges of the spool; Fig. 3, is an outer face view of the other flange; Fig. 4, is a view in side elevation of the spool mounted on a supporting-frame therefor and showing the parts in their operative positions; and Fig. 5, is a fragmental perspective view of a portion of the body of the spool.

Like numerals of reference refer to corresponding parts throughout the different views of the drawing.

The reference numeral 10, designates the body of the spool, which may be made of any suitable size and material, but tubular in form, and is provided at one of its ends with an inwardly extending lug or projection 11, to engage a recess 12, formed on the in-

wardly extended and circular portion 13, of one of the flanges of the spool. The body 10, is provided in its middle portion with an opening 14, and has secured on its inner surface a block 15, which is provided with a headed extension 16, projecting outwardly so as to be about flush with the outer surface of the body. This projection is used to engage an opening in the end of the perforated sheet so that the same may be wound on the roller and securely held in its wound position. The flange 17, for one end of the body of the spool, is provided on its inner surface with the inwardly extended circular portion 18, having a recess 12, to fit in one end of the body 10, and to engage the lug 11, respectively, and said flange also has centrally located therein a sleeve 18, in which is located one end of a shaft 19, which has its bearings 75 in one of the upright portions 20, of the supporting frame 21, for the spool, which frame may be of the ordinary or any preferred construction.

As shown in Figs. 1, and 4, the sleeve 18, 80 has seated therein a set-screw 22, to engage the shaft 19, and said shaft may be provided with a pulley or gear to which power may be applied for driving the same. The flange 24, for the other end of the body 10, is provided with an inwardly extended circular portion 25, to fit in the end of the tubular body 10, and is provided with a central opening 26, to receive a portion of a shaft 27, which is journaled in the other upright 90 20, of the supporting-frame, and may be held thereon by means of a set-screw 28.

As shown in Figs. 1, 3, and 4, the shaft 27, is provided with a circumferential groove 29, near the outer surface of the flange 24, 95 to receive one end of a sliding catch 30, which is movably mounted on a plate 31, secured to the flange 24, by means of straps 32, which are extended transversely over said catch or bar, the outer end of which may 100 have a lateral projection 33, by means of which it may be moved back and forth. The plate 31, is provided near its outer end on its outer surface with a lug 34, to act as a stop for the catch bar 30, and to prevent it 105 being displaced.

From the foregoing and by reference to the drawing, it will be readily understood and clearly seen that when the parts are assembled as shown in Fig. 4, the sheets of 110 music can be readily wound on the body 10, or unwound therefrom, and that by disen-

gaging the catch bar 30, from the groove 29, in the shaft 27, and by loosening the said screw 28, said shaft may be removed from its opening 26, in the flange 24, when said 5 flange can be removed from the body 10, after which the body may be removed from the flange 17, so that another spool body of the same construction may be placed in position at one of its ends on the flange 17, and 10 have the flange 24, fitted to its other end, which latter flange may be quickly mounted on the shaft 27, by placing the same in its central opening.

Having thus fully described my invention 15 what I claim as new and desire to secure by Letters-Patent is—

1. In a spool having end flanges, a shaft fixed in one of said end flanges, a second shaft fixed against movement on which the 20 other of said end flanges is rotatably mounted, said fixed shaft being formed with an annular groove, and a catch having radial movement mounted wholly on said flange and coöperating with said groove, whereby 25 the flange is fixed against endwise movement on the shaft while adapted for free rotary movement.

2. The combination with a frame, a shaft 30 rotatably mounted therein, a shaft fixed therin, and a spool including end flanges directly engaging and supported upon said shafts, of radially-movable means carried by

one of said flanges and having its inner terminal coöperating with a groove formed in said fixed shaft, and means carried by the 35 remaining flange to secure said flange to the rotating shaft.

3. In a device of the character described, the combination with a supporting-frame having side pieces, of a stub-shaft mounted 40 on each of said pieces, one of said shafts having a circumferential groove near its inner end, means on the supporting frame to fix the last named shaft, a flange mounted on each of said shafts and each having an inwardly extended circular portion, a catch mounted for radial sliding movement on the exterior of one of said flanges to detachably engage the groove in one of the shafts, one 45 of said flanges having on the periphery of its inwardly extended circular portion a semi-circular recess disposed with its opening at the periphery of said circular portion, a tubular body interposed between said flanges and fitted around the circular portions thereof, said body having on the inner surface of one of its ends an inwardly extended semi-circular projection to engage the said recess in one of the circular portions of one of the flanges.

OSCAR NELSON.
